UNITED STATES PATENT OFFICE

FRANK ALBACH, OF ST. LOUIS, MISSOURI, ASSIGNOR TO FRED MEDART MANUFACTURING COMPANY, OF ST. LOUIS, MISSOURI, A CORPORATION OF MISSOURI

PLAYGROUND EQUIPMENT

Application filed March 20, 1930. Serial No. 437,540.

This invention relates generally to playground equipment, and more particularly, to certain new and useful improvements in such equipment of the type or class commonly designated as sand-boxes for children's use.

My invention has for its objects the provision of a playground sand-box which comprises few readily and inexpensively manufactured and easily assembled parts, which 10 may be compactly packed for handling and transportation, which is durable in structure and light in weight, which affords convenient, harmless sand-storage for children's play, and which is efficient in the performance of 15 its intended functions, and the improvement and simplification generally of play-ground equipment of the type mentioned.

And with the above and other objects in view, my invention resides in the novel features of form, construction, arrangement, and combination of parts hereinafter described and pointed out in the claims.

In the accompanying drawings,—

Figure 1 is a perspective view of a child's sand-box embodying my invention;

Figure 2 is an enlarged fragmentary partly plan view, showing a corner of the box;

Figure 3 is an enlarged detail vertical sectional view, showing the interior of a corner 30 of the box, the child's seat being omitted;

Figure 4 is a sectional view taken approximately along the line 4—4, Figure 2.

Figure 5 is a broken vertical longitudinal sectional view of the box;

Figure 6 is a fragmentary sectional view taken approximately along the line 6—6, Figure 5;

Figure 7 is a view similar to Figure 3, showing a modified form of corner-post; and

Figure 8 is a horizontal sectional view of the corner of the box shown in Figure 7.

Referring now more in detail and by reference characters to the drawings, which illustrate practical embodiments of my invention, 45 my new sand-box includes, briefly now stated, four vertically disposed or upstanding legs or corner-posts A, opposed end-walls B, opposed side walls C, and floor-forming plates D, D', all constructed preferably of suitable 50 sheet metal rolled, bent, or otherwise formed

into the desired shape and contour, and all of co-operative dimensions for the formation of the complete box.

Each post or leg A longitudinally has substantially the form, as it may be described, 55 of a trough-like member preferably arcuate in cross-section, as shown.

Each post A also preferably tapers in width or length of arc from its upper to its lower end and along its opposite side margins 60 is obliquely flanged outwardly, as at 1, for co-operative connection with a pair of the opposing end and side walls B and C, each of which latter is obliquely flanged at its opposite ends approximately at an angle of 45°, 65 as at 2, 3, respectively, a pair of the flanges 2, 3, in assembling the box-parts, being overlapped and presented against the post A approximately along the vertical median line thereof and the walls B and C being preferably 70 detachably secured to the post A as by suitable fastening bolts or the like 4 engaging the flanges 2, 3, and the post A, as best seen in Figures 2 and 4. As so connected together, the oblique flanges 1 of the post A 75 abut substantially flatwise against the outer face of the respective walls B, C, the respective posts A and walls B, C, being further preferably detachably secured together as by means of additional fastening bolts or the like 5 engaging the flanges 1 and the walls B, C. Thus the several legs or posts A and walls B, C, are conveniently joined rigidly together in box-frame formation and provide a firm, substantial support for the floor- 80 plates D, D', each wall B, C, being also formed with a rolled upper margin 6, which terminate just short of the opposite end-flanges of the respective plate, as best seen in Figures 2 and 3, and which are adapted 85 to neatly and re-enforcingly seat in arcuate recesses, as at 7, provided for the purpose in the post A and its flanges 1.

At its upper end, each post A is formed with a horizontally disposed outwardly presented flange 8 adapted to provide a rest for, and to which is preferably detachably secured by fastening elements 9, a disk-shaped member E adapted to provide a seat for the 95 convenient use of the child. 100

The walls B, C, are of reduced width relatively to the length of the posts A and are so fixed and disposed with relation to the posts A, as shown, as to be preferably somewhat elevated over or spaced upwardly from the ground or other supporting surface upon which the box may be disposed, and at and along its lower margin, each side wall C is doubled or inturned upwardly upon itself, as 5
 10 at 10, to provide a channel or seat 11, which similarly terminates short of the flanged ends of the respective wall, adapted to receive in floor-supporting co-operation downwardly presented side marginal flanges 12 suitably
 15 formed upon the floor-plates D, D', the end walls B being similarly flanged, as at 10', and provided with channels 11' for like supporting cooperation with end marginal flanges 12' formed upon the end floor-plates D. The
 20 latter flanges terminate short of the outer corners of the respective plates D, which corners are downwardly bent to provide tongues 13 adapted to fit against the respective pairs of overlapping flanges 2, 3, and
 25 to which the respective tongues 13 are preferably attached as by the lower one of the fastening bolts 4, as best seen in Figure 4. The intermediate floor-plate or panel D' is also provided at its opposite ends with down-
 30 turned flanges 14 adapted to mutually interfit with respective channels 15 provided or formed on the adjacent margins of the end-floor panels D for detachably retaining the floor-plates in co-operative relation. Thus,
 35 in a simple, but convenient and efficient manner, the floor-plates D, D', are supportingly attached to one another and to the box-frame provided by the connected end and side walls B and C and the posts A.

40 Preferably, I may add, the posts A are each provided or formed at its lower end with a pair of inturned horizontally presented foot-members, or toes 16 for increasing the ground-engaging surface of the posts, the floor-plates
 45 D, D', being supported, as described, in somewhat elevated position over the ground.

I might further add that the seats E are each preferably formed of a stamping having an annular downturned flange 17, the 50 corner of the flange being rounded, as shown, and the seats E covering the corners of the box. It will be observed that all the exposed corners of the box are rounded and provide smooth unbroken edges, about which children
 55 may freely play without risk of injury.

The modified form of the box shown in Figures 7 and 8 is substantially identical with the preferred form shown in Figures 1 to 6, both inclusive, except that the respective corner-posts A' are of rectangular cross-section and of uniform width, the seat-supporting flange 8' of each post being of like angular configuration.

My new box in every respect fulfills the objects hereinbefore stated, and it is to be

understood that changes and modifications in the form, construction, arrangement, and combination of the several parts of the box may be made and substituted for those herein shown and described without departing from the nature and spirit of my invention. 70

Having thus described my invention, what I claim and desire to secure by Letters Patent is:

1. A children's sand-box including, in combination, a trough-shaped corner-post, meeting side and end walls having opposed ends presented in overlapped relation in the trough of, and approximately flatwise against, the corner-post, and means engaging the abutting corner-post and overlapped ends of said walls for conjointly securing the walls together and to the corner-post. 75

2. A children's sand-box including, in combination, a trough-shaped corner-post, meeting side and end walls provided at an end with obliquely laterally presented flanges, said flanges in opposed overlapping relation being presented in the trough of, and approximately flatwise against, the corner-post, and fastening means engaging the abutting corner-post and flanges for securing the walls together and to the corner-post. 80

3. A children's sand-box including, in combination, a trough-shaped corner-post provided at and along its side margins with obliquely outwardly presented flanges, side and end walls having contiguous flanged ends presented in overlapped relation in the trough of, and approximately flatwise against, the corner-post, said post flanges being adapted to abut flatwise against the outer face of the respective walls, and fastening members engaging said post flanges and the walls for securing the post and walls together. 95

4. A children's sand-box including, in combination, a trough-shaped corner-post provided at and along its side margins with obliquely outwardly presented flanges, side and end walls each provided at an end with an obliquely presented lateral flange, said wall flanges in opposed overlapping relation being presented in the trough of, and approximately flatwise against, the corner-post and the post-flanges being adapted to abut flatwise against the outer face of the respective walls, and fastening members for securing the post and walls together, some of said fastening members engaging the post-flanges and walls and others of said fastening members engaging the wall-flanges and the post. 100

5. A children's sand-box including, in combination, a trough-shaped corner-post provided at and along its side margins with obliquely outwardly presented flanges, side and end members each provided at an end with an obliquely presented lateral flange, said wall flanges in opposed overlapping relation being presented in the trough of, and approximately flatwise against, the corner- 115

120

130

post and the post-flanges being adapted to abut flatwise against the outer face of the respective walls, and fastening bolts for detachably securing the post and walls together, some of said bolts engaging the post-flanges and walls and others of said bolts engaging the wall-flanges and the post.

6. A children's sand-box including, in combination, a trough-shaped corner-post provided in its walls with arcuate opposed inwardly opening recesses, side and end walls having contiguous ends presented in the trough of the corner post and each of said walls having a rounded upper marginal portion seating in the post-recesses, and means engaging the corner post and the walls for securing the same together, said posts being extended upwardly beyond the plane of said recesses to provide an elevated seat-support at the corner of the box.

7. A children's sand-box including, in combination, a trough-shaped corner post provided along its side margins with outwardly presented flanges, said flanges being formed with opposed inwardly opening arcuate recesses, side and end walls having contiguous ends presented in the trough of the corner-post and each of said walls having a rounded upper marginal portion seating in said flange-recesses, and means comprising fastening members engaging said flanges and the walls for securing the walls and post together, said posts being extended upwardly beyond the plane of said recesses to provide an elevated seat-support at the corner of the box.

8. A children's sand-box including a trough-shaped corner-post, side and end walls secured to and having contiguous ends presented in the trough of the corner-post, said post being vertically extended above the plane of the upper margins of said walls and formed at its upper end with a lateral flange, and a seat-member disposed horizontally upon said flange and covering the corner-post and the adjacent portions of said walls.

9. A children's sand-box including connected upstanding meeting side and end walls integrally bent inwardly and upwardly along their lower margins to provide upwardly opening channels, and a floor-plate comprising a plurality of panels disposed horizontally to said walls and having downwardly presented marginal flanges adapted to be supported in said channels.

10. A children's sand-box including a floor-plate comprising a plurality of panels, some of said panels having marginal channels and another of said panels having down-turned flanges adapted to be supported in said channels.

In testimony whereof, I have signed my name to this specification.

FRANK ALBACH.
